(57) **CLAIM**

The ornamental design for a glove with dotted zig zag texture as shown and described.

DESCRIPTION

FIG. 1 is a front elevation view showing the new, original, and ornamental design of a glove with dotted zig zag texture, the square area indicated by broken lines and the number seven correspond to the close-up view shown in FIG. 7; FIG. 2 is a rear elevation view thereof; FIG. 3 is a right side elevation view thereof; FIG. 4 is a left side elevation view thereof; FIG. 5 is a top plan view thereof; FIG. 6 is a bottom plan view thereof; FIG. 7 shows a close-up view corresponding to the square area indicated by broken lines in FIG. 1; and, FIG. 8 shows a cross sectional view of the square area shown by FIG. 7 as viewed in the direction of the arrows shown in FIG. 7. The broken lines pattern areas near the upper wrist shown in FIGS. 1–4 illustrate portions of the article and form no part of the claimed design. All other broken lines demarcate the close-up view and form no part of the claimed design.
